UNITED STATES PATENT OFFICE.

ARNOLD SAWYER CURTIS, OF MARLBORO, MASSACHUSETTS.

ARCH-SUPPORTING SHOE.

Original application filed July 6, 1927, Serial No. 203,851. Divided and this application filed March 5, 1928. Serial No. 259,032.

This invention relates to shoes designed to give effective support to the arch of the foot, and more particularly to the manufacture of insoles adapted to the relief of such infirmities as require special support for the longitudinal arch of the foot. Accordingly the invention comprehends a novel arch-fitting insole and a shoe having such insole as a feature.

10 Insoles of the type referred to have been proposed heretofore and generally they have been successful in their purpose so long as the arch supporting element retains its shape and proper position, but this has been found 15 to be difficult because of the materials used, which may not "stand up" under the heavy strains on the shoe when worn, or because of the difficulty in lasting the upper about the arch support element and drawing it into 20 its proper relation to the last when the shoe is being built.

The object of the present invention is to provide an insole which embodies an arch-support element that is preshaped to fit the 25 step of the last and, in addition, will retain its shape and corrective effect on the foot of the wearer of the shoe into which it is built, under the strains of wear. Accordingly an 30 important feature of the invention resides in the manner in which the insole and its arch-support element are assembled to form a unitary article as will hereinafter be set forth in detail.

To the accomplishment of the above object and such others as may hereinafter appear, as will be understood from the following description by those skilled in the art, the invention comprises the features and combination of parts hereinafter described and 40 then particularly pointed out in the appended claims.

The preferred form of the invention is illustrated in the accompanying drawing in which:

45 Figure 1 is a view, in perspective, of an insole blank having a grain side lip cut at its inside shank;

Figs. 2 and 3 are views in plan and section respectively, of the arch support brace or 50 other element to be received in the shank slit;

Fig. 4 is a view, in perspective, of the ribbed side of a welt insole showing the arch-support brace attached;

55 Fig. 5 is a fragmentary view, in plan, showing in dotted lines the initial assembly of the

arch-support brace with the insole and in the plane thereof, and showing in full lines the final, arch-fitting position of the brace, projecting upwardly and outwardly from the sock face of the insole; and 60

Fig. 6 is a view, in cross-section, of an unbottomed welt shoe having the novel arch-support insole as a feature.

In explaining the invention the manufacture of a welt shoe will be described but those skilled in the art of shoemaking will recognize that the invention is applicable to any type of shoe which uses an insole in its construction.

In the embodiment of the invention illustrated in the drawings an insole blank 10 shaped to fit the outline of the last bottom is fitted with a light lip 12 (Fig. 1), on its grain side or sock face throughout the inside shank. This operation may readily be performed by 15 a Goodyear insole channeling machine fitted with a straight knife and edge gage arranged adjacent to the shank edge of the insole to produce an edge slit 14 parallel thereto. The slit 14 may be made more rapidly in 20 such a machine by running in through the heel-seat and out at the ball-line, as illustrated, but for the purposes of this invention a slit substantially as long as the longitudinal dimension of the arch-support brace 25 25 (Fig. 2) is all that is required. Thereafter, for a welt insole, the flesh side or tread face is fitted with a sewing rib 18 in any approved manner which provides a channel 20 and feather 22. It will be observed, from Fig. 30 4, that the base of the grain side lip slit 14 is somewhat inward of the between-substance or base of the sewing-rib 18 affording ample depth for receiving the brace 16, preferably of a relatively heavy leather such as heeling 35 stock.

The arch-support element 16 has somewhat the shape of a box-toe but is longer in proportion to its width and its outer or arch fitting portion 24 (Fig. 2) is larger than its inner 40 or securing margin 26. The portion 24 must be large enough to embrace the instep of the last while the portion 26 requires only sufficient material for anchorage to the insole. As seen from Fig. 3 both longitudinal edges 45 of the brace 16 are skived as is requisite for good shoemaking.

Referring now to Fig. 5 (dot and dash lines) it will be observed that the outcurve 50 of the inner edge 28 of the element 16 is 55

flatter than the incurve of the edge slit 14. In order to seat the edge 28 against the base of the slit 14, as in Figs. 4 and 6, it is necessary to flex the brace 16 longitudinally. If 5 the element 16 is bent so that it is convexed toward the sock face of the sole then, when seated in the edge slit 14, it will stand upward and outwardly relative to said sock face and will have a shape for fitting under 10 the instep of the foot of the wearer of the shoe. The lip 12 is purposely made light so that it will be flexible enough to lift from the feather 22 as the curved element 16 is sprung beneath it to seat at the bottom of the slit 14. 15 In Fig. 5 (full lines) the arch-fitting element 16 is shown in its final, flexed form the curved form of the brace having lifted the lip 12 slightly from the feather. In practice one end of the brace 16 having first been properly 20 positioned in the slit 14, it is stapled to the feather 22, as at 30 Fig. 5, driving the staple through from the feather and clenching it on the brace beneath the turned or raised lip 12. After having been anchored at one end 25 the element 16 may easily be shaped by pressure toward its secured end to seat completely in the slit 14; its other end is then secured to retain its flexed form and thereafter the intermediate fastenings may be applied. Ob- 30viously any suitable fastening means may be used although metallic staples are preferred. To complete the arch-fitting insole the under side of the lip 12 is cemented, and is then laid down on the marginal portion 26 of the 35 shaped and upstanding element 16 in any convenient manner as by a stick.

The insole is now ready for assembly on the last with the counter and upper materials. It will be observed that the insole blank 10 and arch-fitting support 16 are firmly secured together and the two elements may be handled as a unitary article in the further shoemaking processes. When the insole is placed on the last bottom the preshaped brace 16 fits against 40 the contour of the instep of the last and no substantial shaping thereof is required during the lasting operation. As a result superior shoemaking is attained. Attention is particularly called to the novel process of 45 assembling the brace and insole blank because the highly important advantage of having the brace retain its arch-fitting form after being built into the shoe is obtained by securing the brace in position after, not before, it has been 50 flexed to fit the arch.

After the upper materials have been lasted 55 the feather 22, at the inside shank, is brought into contact with the under side of the brace (Fig. 6), the slightly lifted lip 12, however, aids in causing the insole to fit the last bottom at the shank and permits easier and more perfect lasting at this difficult part of the shoe. The shoe is thereafter bottomed as usual, a 60 welt 32 being first inseamed to the sewing-

rib 18 in making a welt shoe as illustrated in 65 Fig. 6. It will be observed that in a welt insole the brace 16 is secured (see Fig. 6) above the plane of the inseam and between-substance leaving the feather wholly unobstructed and hence not interfering in any way 70 with the process of lasting as at present performed. No regard whatever need be paid by the laster to the arch-fitting brace because it assumes its proper position in the shoe on 75 assembly of the insole with the last, being a unitary part of the insole, and lies during the lasting operation entirely below the tread face of the insole and the marginal portion of the upper materials that are being manipulated. 80

This application is a division from an application Serial No. 203,851, filed July 6, 1927, entitled Process of making arch-support insoles in which application will be found claims to the novel process of manufacturing the arch-support insole and the shoe claimed herein. 85

The nature and scope of the invention having been indicated and the preferred construction of the insole and the shoe having 90 been specifically described, what is claimed as new, is:—

1. An arch-support insole having an edge slit between the heel-breast and ball lines at 95 its inside shank, and an arch-supporting element extending upwardly and outwardly from the margin of the insole and secured within said slit. 100

2. An arch-support insole having an edge slit at its inside shank, forming a grain side 100 lip, and an arch-supporting element secured within said slit to the marginal portion of the insole lying below said lip. 105

3. An arch-support insole having an edge slit at its inside shank, and an arch-supporting element shaped to fit the contour of the instep portion of the last at its inside shank, seated in said slit and held by said seating to stand upwardly and outwardly with relation to the sock face of the insole. 110

4. A shoe having an insole, upper materials and outsole, said insole being slit at its inner edge between the heel-seat and ball lines, said slit having a lateral arch support wing secured therein to stiffen the upper materials 115 beneath the arch of the foot. 115

5. A shoe having an insole, upper materials and an outsole, said insole having secured to its inside shank, a flexible sheet leather brace pre-flexed to stand upwardly and outwardly 120 from the sock face of the insole and held from flattening by securement of the lower edge in flexed condition to the margin of the insole, to fit under the instep of the wearer of the shoe and stiffen the upper materials beneath 125 the arch of the foot. 125
